UNITED STATES PATENT OFFICE.

ALFRED GOUNELLE, OF MARSEILLES, FRANCE.

DESIGN FOR A BOTTLE.

SPECIFICATION forming part of Design No. 34,860, dated July 30, 1901.

Application filed June 21, 1901. Serial No. 65,514. Term of patent 14 years.

To all whom it may concern:

Be it known that I, ALFRED GOUNELLE, a citizen of the Republic of France, residing at No. 18 Cherchelle street, Marseilles, France, have invented and produced a new and original Design for Bottles, of which the following is a specification, reference being had to the accompanying drawings, forming part thereof, in which—

10 Figure 1 is a front elevation of a bottle embodying my newly-invented design. Fig. 2 is a transverse section on the line xx of Fig. 1.

15 As shown in the drawings, the leading or material feature of my design consists of the main body A, which is sectionally square and has the form of a truncated pyramid, the lower edge or periphery B of which is rounded, the vertical edge C being similarly rounded, and the four sides of the bottle uniting 20 at the top and being inwardly curved at D

and projecting upwardly in the form of a tapered neck E, with the exteriorly-straight slightly-enlarged mouth F. The base G of the bottle is upwardly projected, as shown in Fig. 1, and exteriorly concaved or formed 25 with a circular recess.

Having fully described my invention, what I claim as new, and desire to secure by Letters Patent, is—

20 The design for a bottle herein shown and described.

In testimony that I claim the foregoing as my invention I have signed my name, in presence of the subscribing witnesses, this 31st day of May, 1901.

ALFRED GOUNELLE.
